 Claims priority, application Germany May 25, 1959
 8 Claims. (Cl. 23—230)

The present invention relates to a method of chemical testing of oils and particularly to a rapid method of determining the neutralization number of mineral lubricating oils, as a measure of the degree of aging or change in stability of the oil, and to an article of manufacture for determining the acidity of oils.

It is well known that in storage or during use various types of oils, such as mineral oils, tend to form or become contaminated with acidic materials. When the formation of these contaminants in a given oil is greater than a certain value the oil becomes acidic and in the case of mineral lubricating oils is the cause of wear and corrosion of engine parts.

The determination of the acidity which develops in oils has long been a difficult problem and very time-consuming. Measuring the neutralization number by standard U.S. methods such as the ASTM methods or the German DIN method requires laboratory facilities which are not practical for the average user of such products such as the gas station attendant or fleet operator for they generally lack time, training, and proper facilities for carrying out the standard procedure.

The neutralization number is a measure of the acidity and is defined as the number in mg. of KOH needed to neutralize the free acids in one gram of the material tested. According to the German method DIN 51,558 which is essentially equivalent to ASTM D664-58 method, the neutralization number is determined by weighing an oil sample, dissolving the sample in a solution of alkali blue 6B in an ethanol-benzene mixture and titrating the solution with $\frac{1}{10}$ N-alcoholic caustic potash solution until the blue color of the solution changes to red.

However, under what might be termed "field" conditions, as contrasted with laboratory conditions, it is often desirable to see at a glance the degree of aging of an oil. The determination of the neutralization number according to the above standard methods is normally limited to the laboratory and in addition is a very time-consuming and expensive operation.

A method has now been found which makes it possible to obviate the elaborate laboratory procedure and to determine the neutralization number rapidly and sufficiently accurately for the indicated purpose.

In accordance with the present invention, it has been found that the determination of the degree of acidity of mineral oils can be rapidly determined by use of a particular solid substance in tabletted form which is capable of neutralizing the acids present in the oil. The solid substance is an alkali metal salt of a nitrophenol having a dissociated constant of from 5.3×10^{-9} to 10×10^{-9} , such as sodium or potassium m-nitrophenate. The compound preferably is monohydrate sodium m-nitrophenate ($C_6H_4(NO_2)ONa \cdot H_2O$). A mixture of the sodium m-nitrophenate and an inert carrier material is suitably so tabletted that each tablet contains 3.19 mg. of

which corresponds to an alkaline content of 1 mg. of KOH. It is also possible to produce tablets corresponding to a larger or smaller quantity of KOH, for instance 0.5, 2, 4, 5, etc. mg. of KOH. In practice, two types of tablets can be suitably used, viz., tablets corresponding

2

to 5 mg. of KOH and tablets corresponding to 1 mg. of KOH, it being possible to produce the latter in such a way that they can be readily broken up into two equal parts. These tablets are new articles of manufacture and are easily and simply used for determining the neutralization number of oils in accordance with the present invention.

The inert carrier material for the alkali nitrophenate may be any solid hydrocarbon which is soluble in a suitable indicator of a mixture of alcohol and benzene solution, such as specified for example in the German method series DIN 51,558, Section 7.1.

The inert carriers may include solid hydrocarbons such as waxy materials, polyaromatics such as unsubstituted or alkyl-substituted naphthalenes, anthracenes or phenanthrenes, e.g., naphthalene, anthracene, phenanthrene, tetralin, decalin, chrysene, indene, C_{1-20} alkyl naphthalene, anthracene, and phenanthrene; phenanthrene has been found to be particularly suitable.

Indicators which are suitable for practicing the invention are any of the well known organic acid-base indicator compounds or any combination thereof, which change color in a desired pH range. Preferred indicators are those which develop strong colors, are stable in air for at least one or two minutes, and are not sensitive to short exposures to the small atmospheric concentrations of carbon dioxide.

Useful indicators may include a wide variety of compounds of which are preferred sulfonic acid derivatives or salts thereof, such as sodium salt of triphenyltriamino triphenylcarbinol sulfonic acid, sold under the trade name alkali blue 6B, p-benzene sulfonic acid-azo-alpha-naphthylamine, 4-amino-1-naphthene-azo-benzene-4'-sulfonic acid, etc.

To determine the neutralization number by the method of this invention a certain volumetric quantity of a test oil is introduced into the test vessel (the specific gravity of a mineral oil is approximately 0.9) and a solution of the indicator such as alkali blue 6B in an alcohol-benzene mixture added as specified by the German method DIN 51,558, Section 7.1. The amount of oil present in the solution mixture is not critical, the main requirement being that the oil should be completely dissolved in the solution and that the entire mixture be fluid. In general, about 5 to 10 ml. of oil to 20 to 40 ml. of indicator solution is desirable and practical. Preferably, the indicator solution contains about 0.3 mg. alkali blue 6B per ml., the ratio of alcohol to benzene being 2:3.

After addition of the alkali blue solution the tablets are added individually until the blue solution turns red. The test vessel is shaken after addition of each tablet and left to stand until the tablet disintegrates. When correctly tableted, the tablets disintegrate within 10-20 seconds, so that the neutralization number can be determined in the shortest possible time.

An illustration of the applicability and dependability of the present method is as follows: To a graduated flask, with a ground glass fitting, is added about 11 ml. (10 grams) of transparent oil, or 5.5 ml. (5 grams) if the oil is not transparent. The alkali-blue 6B solution as described above is added to the oil to a mark on the vessel designated about 20 ml. The vessel is closed by means of a ground-glass stopper and shaken to dissolve the oil in the alkali blue solution. The required number of sodium m-nitrophenate tablets is added until the color change from blue to red is observed.

The neutralization number is calculated from the consumption of tablets.

Test 1

Vessel filled up to 5.5 ml. or approximately 5 grams of oil. After addition of 5 tablets (each corresponding

to 1 mg. of KOH) the solution was still blue; after addition of 5.5 tablets the solution was red. Hence the end point was therefore between 5 and 5.5 tablets corresponding to a neutralization number between 1 and 1.1.

Test 2

Vessel filled up to 11 ml. or approximately 10 grams of oil. After addition of 4 tablets (each corresponding to 1 mg. of KOH) the solution was still blue, after addition of 4.5 tablets the solution was red. Hence the end point was somewhere between 4 and 4.5 tablets, corresponding to a neutralization number between 0.4 and 0.45.

Test 3

Vessel filled up to 5.5 ml. or approximately 5 grams of oil. After addition of 7 tablets (each corresponding to 5 mg. of KOH) and 2 tablets (each corresponding to 1 mg. of KOH) the solution was still blue; after a further addition of 1 tablet (corresponding to 1 mg. of KOH) the solution was red, indicating a neutralization number between 7.4 and 7.6.

The following tabulation shows a comparison between the determination of the neutralization number of some mineral oils according to German method DIN 51,558 and the determination of the neutralization number according to the method of the present invention and with tablets containing phenanthrene as carrier material and sodium m-nitrophenate as active material in such a quantity that the tablets correspond to 5 or 1 mg. of KOH, half tablets of the latter type of tablets also being used in some instances.

Test No.	Oil	Determination with Tablets				Neutralization number	Neutralization Number According to DIN 51,558		
		Vessel Filled up to Mark, ml.	Number of Tablets Used						
			Corresponding to 5 mg. of KOH	Corresponding to 1 mg. of KOH

The method described can be used both with mineral oils and with fatty oils and synthetic oils and mixtures of oils. The specific gravity of the oil to be tested should, of course, invariably be considered when measuring the oil sample.

We claim as our invention:

1. A method of determining the neutralization number of mineral oils which are subject to contamination with

acidic substances and concomitant deterioration which comprises measuring a sample of the oil and dissolving it in an alcohol-benzene solution containing an indicator and dissolving therein the number of tablets having dissociation constants of from 5.3×10^{-9} to 10×10^{-9} of alkali nitrophenate until there is a visual color change.

2. The method of claim 1 wherein the tablets comprise an admixture of an inert oil-soluble hydrocarbon solid and the alkali nitrophenate is sodium m-nitrophenate.

3. The method of claim 2 wherein the inert oil-soluble hydrocarbon solid is phenanthrene.

4. The method of determining the neutralization number of mineral oils which are subject to acidic substances and concomitant deterioration which comprises measuring a sample of the oil and dissolving it in an alcohol-benzene solution containing alkali blue 6B and dissolving therein the number of tablets of phenanthrene-sodium m-nitrophenate, the amount of phenate present being equivalent to 1-5 mg. of KOH until there is a visual color change.

5. An article of manufacture useful for determining the neutralization number of mineral oils, a tablet of an oil-soluble neutral hydrocarbon solid admixed with an alkali metal nitrophenate having dissociation constants of from 5.3×10^{-9} to 10×10^{-9} in integral multiple of amounts stoichiometrically equivalent to 1-5 mg. of KOH.

6. The article of claim 5 wherein the hydrocarbon is phenanthrene and the nitrophenate is sodium m-nitrophenate.

7. An article of manufacture useful for determining

the neutralization number of mineral oil, a tablet of phenanthrene admixed with sodium m-nitrophenate in an amount stoichiometrically equivalent to 1 mg. of KOH.

8. An article of manufacture useful for determining the neutralization number of mineral oil, a tablet of phenanthrene admixed with sodium m-nitrophenate in an amount stoichiometrically equivalent to 5 mg. of KOH.
